ATTORNEY.

UNITED STATES PATENT OFFICE.

WILLIAM CONRY, OF LAPORTE, INDIANA.

BARREL.

1,356,041.

Specification of Letters Patent. Patented Oct. 19, 1920.

Application filed March 12, 1920. Serial No. 365,131.

To all whom it may concern:

Be it known that I, WILLIAM CONRY, a citizen of the United States, residing at La-
porte, in the county of Laporte and State of
5 Indiana, have invented certain new and use-
ful Improvements in Barrels, of which the
following is a specification.

The invention relates to metallic ship-
ping and storing receptacles and has for its
10 object to provide a metallic barrel, particu-
larly adapted for shipping and storing
rosin, tar and the like and so constructed
that the cylindrical body portion of the
barrel may be shipped in a flat condition,
15 then formed into a cylinder for the recep-
tion of the rosin or tar and to provide barrel
heads for the ends of the cylindrical
body portion said barrel heads being pro-
vided with means adapted to be embedded
20 in the material for holding said heads in po-
sition in the ends of the cylindrical body
member.

A further object is to provide a metallic
shipping receptacle for rosin and other
25 plastic materials, which plastic materials
are placed in the receptacles and allowed to
harden therein and to provide sheet metal
heads for said receptacle which heads are
reinforced by wooden disks so as to lend
30 stiffness to the barrel as a whole. It is also
an object to provide U-shaped members hav-
ing their arms extending through apertures
in the heads, which arms are twisted so that
35 they will securely embed in the material
within the receptacle when the same dries,
said U-shaped members also forming means
whereby when the same are severed the re-
ceptacle head may be easily removed from
the body thereof.

40 With the above and other objects in view
the invention resides in the combination and
arrangement of parts as hereinafter set
forth, shown in the drawings described and
claimed, it being understood that changes
45 in the precise embodiment of the invention
may be made within the scope of what is
claimed without departing from the spirit
of the invention.

In the drawings:—

- 50 Figure 1 is a top plan view of the barrel.
Fig. 2 is a vertical sectional view through
the barrel taken on line 2—2 of Fig. 1.
Fig. 3 is a perspective view of one of the
U-shaped head holding members before the
55 ends thereof have been twisted.
Fig. 4 is a detail view of the overlapping

joint for securing the edges of the sheet of
metal forming the body of the barrel.

Referring to the drawings, the numeral 1
designates a cylindrical body member 60
formed from a single sheet of metal, the
edges of said sheet of metal, when the same
are brought together form a cylindrical
body member, being interlocked as shown
at 2 so that the cylindrical body may be 65
formed as desired, however it is to be under-
stood that it is the intention if so desired to
ship the sheets to the point of assembling in
flat form, and then to set up the barrels as
needed. After the cylindrical body member 70
1 has been formed a head 3 is placed in one
end of the member 1, which head comprises
a metallic disk 4 and a wooden reinforcing
disk 5. The disks 4 and 5 are provided
with registering apertures 7 through which 75
apertures the arms 8 of U-shaped head se-
curing members 9 pass, said U-shaped mem-
bers forming means for holding the disks 4
and 5 together and also forming means for
holding the head in the end of the cylin- 80
drical body member after the rosin or other
plastic material solidifies by means of the
twisted ends 10 of the arms 8 which are em-
bedded in the plastic material. After the
rosin 11 has been placed in the body mem- 85
ber 1, a similar head 3 to the head used in
the bottom of the cylindrical member is
placed in the upper end thereof. The head
in the upper end of the cylindrical body
member is also provided with a U-shaped 90
member similar to the U-shaped member 9
used in the bottom head and is adapted to
hold the head in the upper end of the cylin-
drical body member in a similar manner.

When it is desired to remove the mate- 95
rial from the cylindrical body member it
will be seen that it will only be necessary
to sever the U-shaped members and bend
the severed ends upwardly as shown at a
in dotted lines in Fig. 2, then raise the disks 100
4 and 5 as shown in dotted lines in Fig. 2,
thereby removing the heads and allowing
access to the interior of the receptacle, this
operation repeated at both ends of the re-
ceptacle. However, if so desired the inter-
locked joint 2 may be opened and the sheet
of metal forming the cylindrical body mem-
ber flattened out so as to allow the removal
of the solidified contents in bulk.

From the above it will be seen that a me- 110
tallic barrel or receptacle is provided, which
receptacle may be shipped in a collapsed

or knock-down form, then set up at the point of filling so as to reduce cost of shipment. It will also be obvious that a barrel is provided which is particularly adapted for shipping rosin, tar and other plastic materials wherein it will be possible to hold the heads in the ends of the cylindrical body member by providing said heads with portions or members adapted to be embedded 10 in the material.

The invention having been set forth what is claimed as new and useful is:—

1. A receptacle for plastic materials comprising a cylindrical body member, cylindrical reinforced heads in the ends of said body member, U-shaped flexible members carried by the heads, the arms of said U-shaped members extending inwardly through apertures in the heads and having their ends embedded in the plastic material for holding said heads in position, whereby upon severance of said members intermediate their ends the parts thereof may be bent to permit the heads to slide therefrom.
- 25 2. A receptacle for plastic materials comprising a cylindrical body member, cylind-

rical reinforced heads in the ends of said body member, flexible U-shaped members carried by the heads, the arms of said U-shaped members extending inwardly 30 through apertures in the heads and having their ends twisted and embedded in a plastic material for holding said heads in position, whereby upon severance of said members intermediate their ends the parts thereof may be bent to permit the heads to slide therefrom.

3. A receptacle for plastic materials, comprising a body member, heads in the ends of said body member, flexible U-shaped members carried by the heads, the arms of said U-shaped members extending inwardly 40 through apertures in the heads, said arms being twisted beyond the inner faces of the heads and adapted to be embedded in the 45 plastic material for holding the heads in position, whereby upon severance of said members intermediate their ends the parts thereof may be bent to permit the heads to slide therefrom.

In testimony whereof I affix my signature.

WILLIAM CONRY.
